UNITED STATES PATENT OFFICE.

FRANK L. CAPPS, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

TALKING-MACHINE.

1,291,398.

Specification of Letters Patent. Patented Jan. 14, 1919.

Application filed July 1, 1915. Serial No. 37,550.

To all whom it may concern:

Be it known that I, FRANK L. CAPPS, a citizen of the United States of America, and resident of Bridgeport, Connecticut, have invented a new and useful Improvement in Talking-Machines, which invention is fully set forth in the following specification.

This invention relates especially to the tone-arm, the amplifier and the connecting parts which form the tone-passage, together with the supporting elements therefor.

One object of the invention is to provide a sheet metal construction which can be cheaply manufactured and which is superior to earlier constructions in acoustic qualities, simplicity, lightness and beauty. Another object of the invention is to provide an improved universal joint between the tone-arm and the tone-tube.

The invention can be embodied in any of a number of ways, and in the accompanying drawings, for the sake of illustration, I have shown two embodiments. It will be understood, however, that the invention is not limited to the exact constructions shown as other constructions can embody the invention as defined in the claims appended to this specification.

Of the drawings,

Figure 1 is a fragmentary side view of a graphophone of the horn type embodying the invention, certain parts being broken away for the sake of clearness of illustration;

Fig. 2 is a detail perspective view of the tone-arm;

Fig. 3 is a plan view of the combined tone-tube and bracket;

Fig. 4 is a rear elevation of the combined tone-tube and bracket;

Fig. 5 is a fragmentary vertical sectional view of the combined tone-tube and bracket and also shows the universal joint between the tone-tube and the tone-arm;

Fig. 6 is a plan view of the tone-tube elbow which connects with the horn;

Fig. 7 is a vertical sectional view showing parts of a graphophone of the "hornless" type embodying the invention;

Fig. 8 is a perspective view of the combined tone-tube and bracket shown in Fig. 7;

Fig. 9 is a view partly in section showing the tone-arm of the construction shown in Figs. 7 and 8.

Referring to the drawings, 1 represents

the main frame or case in which are positioned the motor, the governor and the other usual parts, 2 is the rotary record table and 3 is a record supported thereon. 4 represents the reproducer which may be of any usual or preferred form. The reproducer is suitably connected through a reproducing elbow 5 with a tone-arm 6 provided with an elbow 7. So far as some of the features of the invention are concerned, the tone-arm and elbows may be formed in any of the well known ways, but I prefer, however, to provide a tone-arm and elbows of an improved and novel construction. The main part 6 of the tone-arm is formed of two initially separate pieces of sheet metal which, after being cut to proper shape, are suitably pressed and bent to form two half tubes. These two half tubes are joined along their longitudinal edges preferably by means of brazing or soldering. In the drawings the line 6' indicates one of the two joints, but it will be understood that in the finished product the two parts may be so nicely joined as to make the line of joining invisible, especially after one of the usual finish processes has been employed. The elbows 5 and 7 are also each formed of two initially separate pieces of sheet metal pressed into the proper shape and afterward joined in the way already described. Preferably, the tubular part 6 is formed with an enlarged or flanged section 8 at its smaller end to receive the elbow 5 which can be secured in place in any suitable manner, as for instance, brazing. Preferably the section 6 and the elbow 7 are joined by means of a ring 9 which can be brazed or otherwise secured in position. Preferably, as shown in Fig. 2, the plane of joining of the two parts of the elbow 5 is at right angles to the plane of joining of the two parts of the section 6 in order that the joints will not register with each other longitudinally. In this way added strength is secured.

The elbow 7 is provided at its end with a spherical section 10. Projecting from this spherical section are two oppositely positioned trunnions 11—11 which, for reasons that will presently appear, are preferably the end parts of a pin 12 which extends from one side of the spherical section to the other. Preferably, for reasons to be hereinafter stated, the trunnions (and the entire pin when used) are located eccentrically of the

sphere and on the side thereof toward the main portion of the elbow.

For connecting the tone-arm with the amplifier and also for supporting the tone-arm (and sometimes the amplifier), I provide a combined tone-tube and bracket which is mounted upon the case 1. The tone-tube is connected with the amplifier by means of a suitable elbow which can be constructed according to preference either separately from the tone-tube or integrally therewith. In Figs. 1, 3, 4 and 5 I have shown a combined tone-tube and bracket 13 of the sort adapted for a graphophone of the horn type, the tone-tube and bracket in this case serving to support the horn as well as the tone-arm. In this embodiment of the invention the combined tone-tube and bracket has a tube portion 14 and a bracket portion 15 formed integrally of two pieces of sheet metal which are cut to suitable shape, and are then pressed and bent to form the two halves of the completed device. Then these two halves are joined by brazing or soldering in the way already described in connection with the tone-arm. The plane of joining is indicated by 13' in Figs. 3 and 4. The bracket part 15 extends downward and inward and is provided at its lower inner end with a flange 16 which is preferably constructed as a separate piece of metal and is brazed to the two pieces of metal forming the main body part of the tone-tube and bracket, said flange being provided with a plurality of holes 17-17 adapted to receive screws 18 to secure the bracket and tone-tube to the case.

The tone-tube part 14 of the combined device 13 connects at one end (in this case the upper end) with the tone-tube elbow, which in this construction is formed separately. The elbow is indicated by 19, and, as clearly shown in Fig. 6, is formed of two pieces of sheet metal which are bent and united in the way already described in connection with the other parts. The lower end of the elbow fits over the upper end of the tube portion 14 of the combined device 13 so as to be rotatable thereon, and may engage an annular rib 20 formed on the tube portion 14. The two parts of the elbow have pressed into them prior to being joined parts of screw threads which, upon the uniting of the two pieces, register with each other to form a complete series of threads as indicated at 21.

22 represents the horn or amplifier provided at its lower end with a threaded portion adapted to be screwed into the threaded portion of the elbow 19. It will be observed that the horn 22 is supported by means of the elbow and the combined tone-tube and bracket 13.

At the end of the tube portion 14 of the combined device 13 opposite to the tone-tube elbow (in this case the lower end) there

are formed two opposite circumferentially extending open slots 23. The spherical section 10 of the tone-arm elbow already described is of such a size as to extend into and closely fit the lower part of the tube 70 portion 14. The trunnions 11-11 before referred to extend into the open slots 23 and serve to support the tone-arm in its proper position. As the axis of the trunnions is eccentric of the spherical section, 75 the said section is supported with its circle of tube contact above the said open slots 23, thus maintaining a completely closed tone-passage and preventing the escape of sound. To prevent sound vibrations being formed 80 in the hollow bracket part 15, and making disagreeable echoes, I insert at the upper end of the bracket part a plug 24 of felt or other equivalent material. The slots 23 are properly positioned and are sufficiently 85 long to permit the tone-arm to swing horizontally and enable the reproducer to follow the record. The tone-arm can swing vertically either when following an irregular record or when manually lifted, the said 90 trunnions 11-11 serving as pivots. It will be understood that these pivot trunnions must slide horizontally in the slots as the tone-arm is raised or lowered in order to permit the spherical section to swing about 95 its true geometrical center.

In order to prevent any noise caused by looseness and resulting vibration at the joint, I provide a spring 25 which, in the preferred embodiment is secured to the tone-tube at one end and which presses laterally against a pin 12 at its other end, thereby constituting a cantilever spring. Preferably the spring is convex on the side engaging the pin 12 so as to offer little or no 100 opposition to the movement of the tone-arm. This spring also, preferably, is secured to the wall of the tone-tube by means of a rivet having a large head 25^a at its inner end. As clearly indicated in Fig. 5 this 110 head serves as a stop to engage the edge of the spherical section 10 and limit the downward movement of the tone-arm when its free end is not supported by the record.

In Figs. 7 and 8 I have shown the invention embodied in a graphophone of the so-called "hornless" type. The tone-arm 6^a with its elbow 7^a is or may be the same as already described, except that the elbow turns downward instead of upward. Repetition of the full description is unnecessary. 13^a represents the combined tone-tube and bracket, it being possible in this construction to combine the bracket part 15^a with the tone-tube elbow. The bracket part 15^a expands toward its lower inner end where it communicates with an amplifier 26 inside the case. The bracket part is provided with a flange 16^a similar to the flange 16 already described and similarly connected. 130

- As already stated, the lower bracket part 15* in this construction constitutes the tone-tube elbow, it being formed integrally with the tone-tube part 14*. At the end of the 5 tone-tube 14* opposite to the elbow (in this case the upper end) there is connected the tone-arm and tone-arm elbow, the construction in this respect being similar to that already described, except that it is inverted.
- 10 In this construction the rivet and the spring should be connected to the tone tube at the side from which the tone arm extends (instead of from the opposite side) in order that the head of the rivet may properly act 15 as a stop in the way heretofore described.

What is claimed is:

1. In a graphophone, the combination with a reproducer and a tone-tube, of a tone-arm and a reproducer elbow interposed between the reproducer and the tone-tube and each comprising initially separate pressed sheet metal parts joined along longitudinal edges, the joints in said arm and elbow being out of alinement.
- 25 2. In a graphophone, the combination with a tone-arm and an amplifier, of a combined tone-tube and bracket, said bracket extending laterally from and supporting said tone-tube, said combined tone-tube and bracket being interposed between said tone-arm and amplifier and comprising initially separate pressed sheet metal parts brazed together along longitudinal edges.
- 30 3. In a graphophone, the combination with a tone-tube and an amplifier screw threaded at its smaller end, of a tone-tube elbow formed with screw threads to engage the screw threads of the amplifier and comprising initially separate pressed sheet metal parts joined along longitudinal edges.

- 40 4. In a graphophone, the combination with a tone-arm and an amplifier, of a combined tone-tube and bracket and a horn elbow, said bracket extending laterally from and supporting said tone-tube and elbow, and said tone-tube and elbow connecting and supporting said tone-arm and amplifier, the said combined tone-tube and bracket and the said elbow each comprising initially separate 45 pressed sheet metal parts joined along longitudinal edges.

- 50 5. In a graphophone, the combination with a tone-arm and an amplifier screw-threaded at its smaller end, of a combined tone-tube and bracket and a horn elbow connecting and supporting said tone-arm and amplifier, the said combined tone-tube and bracket and the said elbow each comprising initially separate pressed sheet metal parts joined along longitudinal edges, and the said elbow having screw-threads pressed thereto to engage the screw-threads of the amplifier.

- 60 6. In a graphophone, the combination with a case, a tone-arm and an amplifier, of

a combined tone-tube and bracket having a tube portion between the tone-arm and the amplifier and having a hollow bracket portion connected with the tube portion, and a closure for the opening between the said tube and bracket portions.

7. In a graphophone, the combination with a case, a tone-arm and an amplifier, of a combined tone-tube and bracket of pressed sheet metal, said combined tone-tube and bracket having a tube portion between the tone-arm and the amplifier and a hollow bracket portion connected with the tube portion, and a closure for the opening between the said tube and bracket portions.

8. In a graphophone, the combination with a case, a tone-arm and an amplifier, of a combined tone-tube and bracket having a tube portion between the tone-arm and the amplifier and having a hollow bracket portion connected with the tube portion, and a felt plug in the opening between the said tube and bracket portions.

9. The combination in a graphophone, of a tone-tube, a tone-arm having an end positioned within and closely fitting the tone-tube, pivot means maintaining said arm and tube in operative relation, and a spring acting laterally on said end of the tone-arm to prevent vibration.

10. The combination in a graphophone, of a tone-tube, a tone-arm having an end positioned within and closely fitting the tone-tube, pivot means maintaining said arm and tube in operative relation, and a spring within said arm and tube and acting laterally on the aforesaid end of the tone-arm to prevent vibration.

11. The combination in a graphophone, of a tone-tube, a tone-arm having an end positioned within and closely fitting the tone-tube, said tone-arm being movable relatively to said tone-tube about a vertical axis to follow the groove of a record-tablet, a horizontal pivot pin maintaining said arm and tube in operative relation, and a spring acting laterally on said pin to prevent vibration.

12. The combination in a graphophone, of a tone-tube, a tone-arm having an end positioned within and closely fitting the tone-tube, one of said members having oppositely disposed circumferentially extending slots near one end, oppositely positioned trunnions carried by the other of said members and projecting into said slots, and a spring acting laterally on said end of the tone-arm to prevent vibration.

13. The combination in a graphophone, of a tone-tube, a tone-arm having a spherical section positioned within and closely fitting the said tone-tube, and horizontal pivot means maintaining said arm and tube in operative relation, the axis of said pivot being so located eccentrically of the spherical

section as to position the said section with its circle of tube contact beyond said axis.

14. The combination in a graphophone, of a tone-tube, a tone-arm provided with a spherical end section positioned within and closely fitting the tone-tube, one of said members having oppositely disposed circumferentially extending slots near one end, and oppositely positioned trunnions carried by the other of said members and projecting into the slots, the axis of the said trunnions being so located eccentrically of the spherical section as to position the said section with its circle of tube contact beyond the said slots.

15. The combination in a graphophone, of a tone-tube having oppositely disposed circumferentially extending slots near one end, a tone-arm provided with a spherical section positioned within and closely fitting the tone-tube, and oppositely positioned trunnions carried by the spherical section and projecting into the slots, the axis of the said trunnions being so located eccentrically of the spherical section as to position the said section with its circle of tube contact beyond the said slots.

16. The combination in a graphophone, of a tone-tube having oppositely disposed circumferentially extending slots near one end, a tone-arm provided with a spherical section positioned within and closely fitting the tone-tube, oppositely positioned trunnions carried by the spherical section and projecting into the slots, and a spring acting laterally on the spherical section to prevent vibration.

17. The combination in a graphophone, of a tone-tube having oppositely disposed circumferentially extending slots near one end, a tone-arm provided with a spherical section positioned within and closely fitting the tone-tube, oppositely positioned trunnions carried by the spherical section and projecting into the slots, the axis of the said trunnions being so located eccentrically of the spherical section as to position the said section with its circle of tube contact beyond the said slots, and a spring acting laterally on the spherical section to prevent vibration.

18. The combination in a graphophone, of a tone-tube having oppositely disposed circumferentially extending slots near one end, a tone-arm provided with a spherical

section positioned within and closely fitting the tone-tube, a pin extending through the spherical section and terminating in trunnions projecting into the slots, and a spring mounted on the tone-tube and pressing laterally against the pin to prevent vibration.

19. The combination in a graphophone, of a tone-tube having oppositely disposed circumferentially extending slots near one end, a tone-arm provided with a spherical section positioned within and closely fitting the tone-tube, a pin extending through the spherical section and terminating in trunnions projecting into the slots, the said pin being so located eccentrically of the spherical section as to position the said section with its circle of tube contact beyond the said slots, and a spring mounted on the tone-tube and pressing laterally against the pin to prevent vibration.

20. The combination in a graphophone, of a tone-tube having oppositely disposed circumferentially extending slots near one end, a tone-arm provided with a spherical section positioned within and closely fitting the tone-tube, a pin extending through the spherical section and terminating in trunnions projecting into the slots, and a cantaliver spring mounted on the tone-tube and pressing against the pin to prevent vibration, the said spring being convex on the side engaging the pin to permit the pin to move freely with the tone-arm.

21. The combination in a graphophone, of a tone-tube having oppositely disposed circumferentially extending slots near one end, a tone-arm provided with a spherical section positioned within and closely fitting the tone-tube, a pin extending through the spherical section and terminating in trunnions projecting into the slots, a cantaliver spring pressing laterally against the pin to prevent vibration, and a rivet for connecting the spring to the tone-tube having a head positioned to be engaged by the edge of the spherical section to limit downward movement of the tone-arm.

In testimony whereof I have signed this specification in the presence of two subscribing witnesses.

FRANK L. CAPPS.
